Primary Examiner — Nicole C Shiflet(74) *Attorney, Agent, or Firm* — Fred Zollinger**CLAIM**

The ornamental design for a cooking plate for fire pit, as shown and described.

DESCRIPTION

FIG. 1 is an upper perspective view of a first embodiment of the cooking plate for fire pit showing my new design.

FIG. 2 is a lower perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an upper perspective view of a second embodiment of the cooking plate for fire pit showing my new design.

FIG. 10 is a lower perspective view thereof.

FIG. 11 is a front elevation view thereof.

FIG. 12 is a rear elevation view thereof.

FIG. 13 is a left side elevation view thereof.

FIG. 14 is a right side elevation view thereof.

FIG. 15 is a top plan view thereof; and,

FIG. 16 is a bottom plan view thereof.

The dashed lines shown in the drawings are for purposes of illustrating portions of the article that form no part of the claimed design.
